ABSORPTION REFRIGERATION

Walter M. Simpson, Evansville, Ind., assignor to
 Servel, Inc., New York, N. Y., a corporation of
 Delaware

Application April 7, 1951, Serial No. 219,777

11 Claims. (Cl. 62—119)

1

The present invention relates to absorption refrigeration systems and more particularly to an improved heating arrangement for expelling refrigerant vapor from absorption solution in such systems.

One of the objects of the present invention is to provide a combined generator and vapor liquid-lift in the form of a single upright conduit so constructed as to provide the necessary heat transfer surface and cross sectional area to expel vapor and lift liquid at any desired rate.

Another object is to provide a single upright conduit of the type indicated which is heated throughout its length and adapted for use with an absorption refrigeration system of any capacity.

Still another object is to provide a heated vapor liquid-lift conduit with a lower depending skirt portion having undulating folds to increase the heat transfer surface and an upper lift portion of reduced cross-sectional area correlated to the heat transfer surface to produce a vapor velocity sufficient to lift liquid at the desired rate at any particular capacity.

These and other objects will become more apparent from the following description and drawings in which like reference characters denote like parts throughout the several views. It is to be expressly understood, however, that the drawings are for the purpose of illustration only and not a definition of the limits of the invention, reference being had for this purpose to the appended claims. In the drawings:

Fig. 1 is a diagrammatic view of an absorption refrigeration system incorporating the combined generator and vapor liquid-lift conduit of the present invention;

Fig. 2 is an enlarged view of the upright conduit showing its upper liquid-lift portion and lower pleated skirt and enclosed throughout its length by a heating jacket;

Fig. 3 is a transverse sectional view taken on line 3—3 of Fig. 2 showing the radial folds in the lower skirt portion to provide an extended heating surface;

Fig. 4 is a view similar to Fig. 3 taken on line 4—4 of Fig. 2;

Fig. 5 is a sectional side elevational view of a vapor liquid-lift conduit of modified construction;

Fig. 6 is a transverse sectional view taken on line 6—6 of Fig. 5 and showing the wall of the lower portion folded to provide a series of laterally extending wings or pleats to increase the heat transfer surface; and

Fig. 7 is a sectional side elevational view of a 55 The lower ends of the headers 22 and 23 over-

2

vapor liquid-lift of still further modified construction showing the upper lift portion in the form of a cylindrical tube.

Referring to Fig. 1 of the drawings, the invention is shown applied to a vacuum type absorption refrigeration system of the type described and claimed in United States Letters Patent to Albert R. Thomas et al., 2,282,503, issued May 12, 1942, which utilizes water as a refrigerant and 10 a salt solution as an absorbent. The system as illustrated comprises a combined generator and vapor liquid-lift conduit 10, constituting the subject matter of the present invention, a separating chamber 11, a condenser 12, an evaporator 13, an absorber 14, and liquid heat exchanger 15 interconnected for the circulation of refrigerant and absorbent.

The combined generator and vapor liquid-lift conduit 10, later to be described in detail, receives absorption solution from the liquid heat 20 exchanger 15 and utilizes expelled vapor to lift absorption solution into separating chamber 11 for gravity flow through the absorption solution circuit. The separating chamber 11 surrounds the upper end of the vapor liquid-lift conduit 10 and has a curved deflecting baffle 16 overlying the upper end of the lift and a plurality of other baffles 17 for separating liquid entrained in the vapor. The top of the separating chamber 11 is 25 connected to the condenser 12 by a conduit 18 and the outlet from the condenser is connected to the evaporator 13 by a conduit 19 having a device 20 therein for maintaining a pressure differential while permitting the flow of non-condensable gases as described and claimed in a copending application of Norton E. Berry, Serial No. 725,000 filed January 29, 1947.

The evaporator 13 comprises a plurality of horizontally arranged tubes 21 having their opposite ends projecting into laterally spaced headers 22 and 23. Conduit 19 from condenser 12 is connected to one end of the uppermost evaporator tube 21 in header 22. The end of the next lower tube 21 projecting into header 23 has a cup 24 at its end underlying the end of the uppermost tube to receive liquid refrigerant flowing therefrom and direct it for flow through said next lower tube. Each of the tubes 21 has a cup 24 at one end underlying the end of the tube above to cause the liquid refrigerant to flow successively through each tube from the top to the bottom of the evaporator. Between the headers 22 and 23 the tubes 21 are provided with spaced heat transfer fins 25.

The lower ends of the headers 22 and 23 over-

lie openings 26 in the top of the absorber 14. The absorber 14 is in the form of a cylindrical shell having a plurality of vertically arranged serpentine coils 27 and a liquid distributing means 28. The liquid distributing means 28 uniformly distributes absorption liquid over the top of each coil 27 which drips from each coil section onto the next lowermost coil section from the top to the bottom of the coils. Cooling water is supplied to the interior of the coils 27 from any suitable source of supply through a pipe 29 and header 30. Cooling water from the upper ends of coils 27 is delivered through a header 31 and conduit 32 to condenser 12 and cooling water from the condenser is discharged through a conduit 33. Thus, the same cooling water is used to cool the evaporator 13 and condenser 12.

Absorption solution flows by gravity from the separating chamber 11 through the absorption solution circuit back to the base of the upright lift conduit 10. Absorption solution weak in refrigerant flows from the separating chamber 11 to the liquid distributor 28 in a path of flow comprising conduit 34, inner passages 35 of the liquid heat exchanger 15 and conduit 36 connected to the liquid distributor. Absorption solution strong in refrigerant flows from the absorber 14 to the base of conduit 10 in a path of flow comprising conduit 37, outer passages 38 of the liquid heat exchanger 15 and accumulates in the upper part of the liquid heat exchanger casting constituting a leveling vessel 39 and from the leveling vessel through a conduit 40. Leveling vessel 39 has a relatively large volume so that variations in liquid flow in the solution circuit will have a negligible effect on the liquid level x in the vessel during operation of the system.

A purge device 41 as described and claimed in United States Patent to Charles C. Roswell Re. 23,093 issued March 22, 1949, is provided which is in the form of an auxiliary absorber connected to the main absorber 14 to withdraw non-condensable gases from the system. The purge device 41 comprises a vessel connected to conduit 36 to receive absorption solution weak in refrigerant and has a suction pipe 42 extending to the bottom and center of the main absorber 14 where the gases accumulate. A cooling coil 43 in the purge device 41 is connected to the cooling water conduits 29 and 32 and a fall tube 44 depends from the bottom of the vessel. The purge device 41 utilizes a portion of the absorption solution flowing toward the absorber 14 for producing a relative vacuum to withdraw non-condensable gases from the main absorber and deliver them through the fall tube 44 to a riser 45 connected to conduit 37 at its lower end and having a storage vessel 46 at its upper end. With such a construction non-condensable gases are withdrawn from the system and delivered to the storage vessel 46 while the absorption solution is delivered to the conduit 37 flowing toward the base of the upright lift conduit 10.

A concentration control of the type illustrated and described in United States Letters Patent of Lowell McNeely 2,465,904, issued March 29, 1949, is provided for storing liquid refrigerant in accordance with the difference in pressure between the high and low pressure sides of the system. The concentration control comprises a vessel 47 having a conduit 48 connected to receive liquid refrigerant overflowing from the lowermost tube of the evaporator 13 and a conduit 49 connecting

the bottom of the vessel to the base of the upright lift conduit 10. A pressure equalizing conduit 50 is also connected between the top of the vessel and the side of the evaporator header 22.

The upright lift conduit 10 and condenser 12 operate at one pressure corresponding to the condensing temperature of the condenser, for example, one pound per square inch absolute, and the evaporator 13 and absorber 14 operate at a lower pressure corresponding to the vapor pressure of refrigerant in the absorber, for example, one-tenth of a pound per square inch absolute, and the pressure difference is maintained between the condenser and evaporator by the device 20 and between the generator and absorber by liquid columns in conduits 36 and 37. The liquid heat exchanger 15 is located below absorber 14 and during operation of the system solution will stand at a level x in leveling chamber 39 to produce a hydrostatic reaction head h on solution in the upright lift conduit 10 and solution will stand at a level y in conduit 34 connected to conduit 36 through liquid heat exchanger 15 and at a level z in conduit 37.

In accordance with the present invention, the combined generator and vapor liquid-lift 10 is so constructed and arranged as to provide the necessary heating surface and cross-sectional area in a single conduit to lift liquid at the desired rate at any particular capacity. While the present invention is intended to include an arrangement for heating only a portion of the conduit, the entire length of the conduit is heated in the preferred construction.

In the embodiment of the invention illustrated in Figs. 1 to 4, the combined generator and vapor liquid-lift conduit 10 comprises an upper liquid-lifting portion 55 and a lower depending skirt portion 56. The upper liquid-lifting portion 55 may take other forms but preferably comprises a conduit having a throat 57 with a progressively divergent cross-sectional area extending upwardly from the throat and formed as a tapered tube or by flattening the sides of a cylindrical tube as described and claimed in copending applications for United States Letters Patent of Eugene P. Whitlow Serial No. 220,002 filed April 9, 1951.

The lower depending skirt portion 56 is of generally conical form diverging outwardly from the throat 57 to the bottom. The depending skirt portion 56 is in the form of a sheet metal wall pleated with radial outer and inner folds 59 and 60 to form a fluted cone. As shown more clearly in Figs. 3 and 4, the folds 59 and 60 in the sheet metal wall of the skirt portion 56 are arranged closely adjacent each other to provide inner and outer undulating surfaces with each side 61 of the pleats between adjacent folds 59 and 60 providing an additional heat-transfer surface. The degree or depth of the pleats and the conical taper of the skirt portion 56 may be varied to provide the desired heat transfer surface necessary for any particular capacity. In the illustrated embodiment the depth of the pleats formed by folds 59 and 60 progressively increases from the top of the skirt portion 56 to the bottom thereof and extend inwardly toward each other to form an unimpeded circular opening 62 at the center and bottom of the skirt. In other words, the outer folds 59 taper outwardly to provide an outer conical contour and the inner folds 60 taper inwardly to provide an

inverted conical contour. The bottom of the lower pleated skirt portion 56 is closed by a plate 63 having a depending well 64 in alignment with the opening 62 to which the conduits 40 and 49 are connected. With the construction as described above, it will be noted that the lower conical skirt portion 56 provides a passage converging toward the throat 57 and the upper portion 55 provides a passage diverging from the throat.

The combined generator and vapor liquid-lift conduit 10 is enclosed throughout its length by a jacket 65 providing a heating chamber 66 around the lower skirt portion 56 and upper lift portion 55. A conduit 67 at the lower end of jacket 65 is connected to a source of heating medium, such as steam, and a vent pipe 68 is connected to the upper end of the jacket to maintain the steam at atmospheric pressure. Steam supplied to the jacket 65 will contact both the lower skirt portion 56 including the sides 61 and folds 59 and 60 and the lift portion 55 throughout its length. A condensate drain-pipe 69 is connected to the bottom of the jacket 65.

When designing a combined generator and vapor liquid-lift conduit 10, the total heat-transfer surface for expelling the amount of vapor required for the particular capacity and the cross-sectional area required to lift liquid at the desired rate with the amount of vapor expelled are determined. A lift conduit 55 is then selected having the required cross-sectional area and a lower depending skirt portion 56 folded to provide the heat transfer surface required in addition to the surface of the lift portion and attached to the latter below the throat 57. Thus, a conduit 10 is provided which correlates the cross-sectional area at the throat 57 with the heat-transfer surface to produce the desired rate of circulation with a single conduit at any particular capacity. One form of the invention having now been described in detail, the mode of operation is explained as follows.

To initiate operation of the refrigeration system, steam is supplied through conduit 67 to the heating chamber 66 between the jacket 65 and combined generator and liquid-lift conduit 10. The heating steam contacts the walls of the conduit 10 throughout its length including the undulating folds of the depending skirt portion 56. Heat is transmitted from the steam through the walls 61 between adjacent folds 59 and 60 to heat the solution in the radial wings between the walls and thereby expel refrigerant vapor from the solution. The vapor flows upwardly toward the throat 57 and because of the throttling effect of the throat will depress the liquid level to height h below the level x in leveling vessel 39. Due to the designed correlation of the heat-transfer surface to the cross-sectional area of the throat 62, the vapor will flow upwardly through the throat and upper lift portion 55 of the conduit at a high velocity sufficient to lift droplets of liquid at the desired rate. Such droplets of liquid are formed by the violent expulsion of vapor from solution which probably produces a froth or foam which, in turn, is torn apart by the high velocity vapor and coalesces in small droplets. The frictional drag of the high velocity vapor on the surface of the droplets produces a force greater than the force of inertia and gravity of the droplets to impart momentum thereto. As the droplets rise through the upper lift portion 55 of the conduit 10, they are further heated to expel additional vapor. Such additional vapor

would tend to increase the vapor velocity but the force required to lift the droplets becomes progressively less due to the initial momentum of the droplets and decreasing height. As it is desired to merely lift the droplets of liquid to the separating chamber 11 without any excess velocity, the upper lift portion 55 of the conduit has a progressively divergent passage designed to compensate for the additional vapor expelled there-in and the decreased velocity required to lift the liquid into the separating chamber.

The droplets of liquid issuing from the upper end of the lift conduit 10 engage the baffle 16 and are separated from the vapor. The vapor continues to flow through the additional baffles 17 where all of the liquid is removed from the vapor and the latter then flows through the conduit 18 to the condenser 12 where it is condensed to a liquid. Liquid refrigerant flows from the condenser 12 through the restricting device 20 and conduit 19 to the top of the evaporator 13. The liquid refrigerant then flows by gravity through successive tubes 21 from the top to the bottom of the evaporator.

Simultaneously, the absorption solution weak in refrigerant flows by gravity through conduit 34, inner passages 35 of liquid heat exchanger 15 and conduit 36 to liquid distributor 28. The absorption solution is distributed for gravity flow over the serpentine coils 27 of the absorber 14 by the liquid distributor 28 where it absorbs refrigerant vapor and reduces the pressure and temperature at which the refrigerant evaporates in the evaporator 13 to cool the air passing over the tubes 21 and between the fins 25. Absorption solution strong in refrigerant flows by gravity from absorber 14 through the conduit 37, outer passages 38 of liquid heat exchanger 15 and into the leveling vessel 39. From the leveling vessel 39 the solution flows through conduit 40 to the inlet chamber or well 64 at the base of the combined generator and vapor liquid-lift conduit 10 to complete the cycle of operation.

Non-condensable gases accumulating at the center and bottom of the absorber 14 are continuously withdrawn by the purging device 41 and transferred to the storage vessel 46. At the beginning of a period of operation of the refrigeration system, liquid refrigerant will overflow from the lowermost tube 21 of evaporator 13 into the concentration vessel 47 which stores liquid refrigerant until the concentration of the solution has increased to produce an equilibrium condition at the desired evaporator temperature.

In Fig. 5 a modified construction is illustrated in which the lower depending portion 56 of the combined generator and vapor liquid-lift conduit 50 is of rectangular form instead of conical form. As illustrated more clearly in Fig. 6, the depending portion 56 comprises a heat-transfer wall having a plurality of adjacent laterally-extending wings 75 formed by opposite folds 76 and 77 and providing additional heat transfer surfaces 78 between adjacent folds. The top of the laterally-extending wings 75 are closed by a plate 79 preferably cut away between adjacent wings and having a central opening 80 connected to the lower end of the lift portion 55 below the throat 57. The bottom of the laterally-extending wings 75 are also closed by a plate 81 having a centrally located well 82. The form of construction illustrated in Fig. 5 operates in substantially the same way as the construction illustrated in Figs. 1 to 4.

In Fig. 7 a further modified form of construction is illustrated having a straight cylindrical

tube 85 forming the upper lift portion of the conduit instead of a divergent conduit as illustrated in the previously-described constructions. While a combined generator and vapor lift conduit 10 having an upper divergent lift portion 55 is preferred, a straight cylindrical lift portion can be used as illustrated in Fig. 7 but will require an additional reaction heat h to balance the increased forces. It is to be understood, also, that the straight cylindrical lift tube 85 illustrated in Fig. 7 may be used with a lower conical skirt portion 56 illustrated in Figs. 1 to 4. In the form of the invention illustrated in Fig. 7, the lower end of tube 85 at its point of joinder with the depending skirt portion 56 constitutes the restriction or throat for producing the vapor velocity required.

It will now be observed that the present invention provides a combined generator and vapor liquid-lift so constructed as to adapt a single lift conduit to circulate liquid at the desired rate at any capacity. It will also be observed that the present invention provides a single vapor liquid-lift conduit adapted for an absorption refrigeration system of any particular capacity having an additional heating surface formed by a pleated heat-transfer wall depending from the lift portion of the conduit. It will still further be observed that the present invention provides a single conduit heated throughout its length and having sufficient heat-transfer surface and cross-sectional area to produce the desired rate of circulation at any particular capacity.

While several forms of the invention have been illustrated and described herein, it will be understood that further changes may be made in the construction and arrangement of the elements without departing from the spirit or scope of the invention. Therefore, without limitation in this respect, the invention is defined by the following claims.

What is claimed is:

1. In an absorption refrigeration system, an absorption solution circuit having an upright lift conduit for any particular capacity, the parts of said circuit being arranged to maintain a level of absorption solution above the bottom of said lift conduit, the wall of the lower portion of said lift conduit below said liquid level having a plurality of undulating folds to provide the heat transfer surface required to expel vapor in quantities sufficient to continuously maintain a body of vapor above the liquid level therein, means for heating the lower portion of said lift conduit, and the conduit above the undulating fold having a throat for producing a vapor velocity sufficient to lift solution at a controlled rate of relative circulation of vapor and liquid.

2. In an absorption refrigeration system, an absorption solution circuit having an upright lift conduit for any particular capacity, the parts of said circuit being arranged to maintain absorption liquid in said circuit at a level above the bottom of said lift conduit, the lower portion of said lift conduit forming a chamber in said circuit below the liquid level and the wall of said chamber being folded to provide a plurality of adjacent pleats for increasing the heat transfer surface, a throat in the conduit above the lower pleated portion, and means for heating the pleated wall at the lower portion of said conduit to expel refrigerant vapor in quantities sufficient to continuously maintain a body of vapor between the liquid solution and throat.

3. In an absorption refrigeration system, an

absorption solution circuit having an upright conduit, said conduit having an upper lift portion and a depending heat transfer wall folded to provide vertically arranged pleats for increasing the heat transfer surface and directing expelled vapor upwardly toward the lift portion, a throat between the upper lift portion and lower depending wall, the parts of said circuit being arranged to maintain absorption liquid above the bottom of said conduit, means for heating the depending heat transfer wall to expel vapor at a rate to maintain a body of vapor in the conduit below the throat, and the throat having a cross-sectional area to cause vapor to flow upwardly through the lift portion at a velocity sufficient to lift liquid at the required rate.

4. In an absorption refrigeration system, an absorption solution circuit having a single upright conduit, the wall of the lower portion of said conduit being folded to provide a plurality of pleats to provide the heat transfer surface required to expel vapor in quantities sufficient to continuously maintain a body of vapor in the conduit above the liquid level therein, a throat in the conduit above the pleats for producing a vapor velocity to lift liquid at the desired rate, a heating jacket enclosing the entire conduit throughout its length, and means for supplying heating medium to the jacket.

5. In an absorption refrigeration system, an absorption solution circuit having a single upright conduit, said conduit having an upper lift portion and a depending generator portion, the wall of the depending generator portion being folded to provide a plurality of vertically arranged pleats to provide the heat transfer surface required to expel vapor in quantities sufficient to continuously maintain a body of vapor in the conduit above the liquid level, a throat in the conduit above the pleats for producing a vapor velocity to lift liquid at the desired rate, a heating jacket enclosing the entire conduit throughout its length, and means for supplying a heating medium to the jacket.

6. An absorption refrigeration system in accordance with claim 1 in which said conduit has a converging vapor expelling portion and diverging liquid-lift portion with a throat therebetween, the walls of said converging portion being fluted to increase the heat transfer surface and direct expelled vapor toward the throat, a heating chamber surrounding the converging vapor expelling portion, and means for supplying a heating medium to the chamber.

7. An absorption refrigeration system in accordance with claim 1 in which said conduit has an upper lift portion and a lower vapor expelling portion, the lower vapor expelling portion having lateral wings to increase the heat transfer surface, a jacket surrounding the conduit throughout its length to provide a heating chamber, and means for supplying a heating medium to the chamber.

8. An absorption refrigeration system in accordance with claim 1 in which said conduit has an upper lift portion and a depending conical skirt portion, the wall of said skirt portion having radial folds to increase the heat transfer surface, and a heating jacket enclosing the conduit throughout its length.

9. An absorption refrigeration system in accordance with claim 1 in which said conduit has an upper divergent conical lift portion and a depending converging conical portion with a throat

therebetween, the wall of the depending conical portion having radial folds to increase the heat transfer surface, and a heating jacket enclosing the conduit throughout its length.

10. An absorption refrigeration system in accordance with claim 1 in which said conduit has an upper lift portion and a lower vapor expelling portion, the lower vapor expelling portion extending laterally from the sides of the upper lift portion with its wall folded to provide a plurality of 10 adjacent pleats, and a heating jacket enclosing the conduit throughout its length.

11. An absorption refrigeration system in accordance with claim 1 in which said conduit has an upper cylindrical liquid-lift portion and a 15 lower rectangular vapor expelling portion, the wall of the lower vapor expelling portion being

folded to provide a plurality of laterally extending wings, and a heating jacket enclosing the upright conduit throughout its length.

WALTER M. SIMPSON.
